GOLF PUTTER HEAD

Asa F. Whitney, Fort Wayne, Ind., assignor of one-half to Martin J. Dicker, Fort Wayne, Ind.

Application February 7, 1958, Serial No. 49,535

Term of patent 7 years

(Cl. D34—5)

Fig. 1 is a side elevational view of a golf putter head showing my new design with a portion of the hosel broken off for ease of illustration;

Fig. 2 is a top view thereof;

Fig. 3 is a front view thereof;

Fig. 4 is a rear view thereof; and

Fig. 5 is a view in perspective of my new golf putter head design having a portion of the hosel broken off for ease of illustration.

I claim:

The ornamental design for a golf putter head, as shown and described.
